UNITED STATES PATENT OFFICE.

CHARLES EVERETTE SMITH, OF NEW YORK, N. Y.

DESIGN FOR A NECKTIE-HOLDER.

SPECIFICATION forming part of Design No. 27,499, dated August 10, 1897.

Application filed July 3, 1897. Serial No. 643,462. Term of patent 7 years.

To all whom it may concern:

Be it known that I, CHARLES EVERETTE SMITH, a citizen of the United States, residing at New York, in the county of New York and State of New York, have invented and produced a new and original Design for Necktie-Holders, of which the following is a specification, reference being had to the accompanying drawings, forming a part thereof.

10 In the drawings forming part of this specification, Figure 1 is a plan view of a necktie-holder, showing my new and original design; and Fig. 2, a side view thereof, these two views being deemed sufficient to fully illustrate the

15 design.

My newly-designed necktie-holder is composed of spring-wire bent into the shape hereinafter described; and the leading or material feature of my design consists, as shown 20 in the drawings, of a downwardly-directed loop or yoke A, which opens upwardly and the separate sides of which are curved out-

wardly, as shown at B, and then downwardly to form parallel downwardly-directed side arms C, and then forwardly, as shown at E, 25 and then upwardly and slightly inwardly to form supplemental spring-arms F, and then inwardly, as shown at G, and downwardly to form parallel prongs H, which are pointed at their lower ends, as shown at K.

Having fully described my new and original design, what I claim as new, and desire to secure by Letters Patent, is—

The design for a necktie-holder herein shown and described.

In testimony that I claim the foregoing as my invention I have signed my name, in presence of the subscribing witnesses, this 2d day of July, 1897.

CHARLES EVERETTE SMITH.
